UNITED STATES PATENT OFFICE

148,509

DESIGN FOR A COMBINED JAR AND DISPENSING COVER

Mary S. Wright, New York, N. Y.

Application April 23, 1946, Serial No. 128,884

Term of patent 14 years

(Cl. D58—25)

To all whom it may concern:

Be it known that I, Mary S. Wright, a citizen of the United States of America and a resident of the city of New York, Borough of Manhattan, county of New York, and State of New York, have invented a new, original, and ornamental Design for a Combined Jar and Dispensing Cover, of which the following is a specification, reference being had to the accompanying drawing, forming part thereof, in which—

Fig. 1 is a perspective view of a combined jar and dispensing cover embodying my design.

Fig. 2 is a top view thereof.

Fig. 3 is a sectional view taken on line 3—3 of Fig. 2.

I claim:

The ornamental design for a combined jar and dispensing cover, as shown.

MARY S. WRIGHT.
